UNITED STATES PATENT OFFICE

2,428,862

PLATFORM SHOE

William Weinbrot, Brooklyn, N. Y.

Application May 16, 1946, Serial No. 670,240

2 Claims. (Cl. 36—17)

1

This invention relates to a new and improved construction for shoes of the platform type. Such shoes are characterized by a platform sole disposed between the upper and the outer sole, and having a welt associated therewith.

It is one object of the invention to provide a platform sole shoe with a new and improved welt which may be formed of a single elongated strip of leather or other suitable material in a simple and economical manner.

It is another object of the invention to provide a novel welt strip that will connect the upper and the insole with the outer sole without the necessity of inwardly tucking the lower marginal edge of the welt strip between the platform sole and the outer sole as heretofore was the practice.

Still another object of the invention is to provide a welt whose lower marginal portion extends outwardly to form a bead terminating in a horizontal edge, said edge providing for the stitch connection of the welt with the outer sole. By such construction, the welt at its juncture with the outer sole provides a water-proof seal and at the same time adds to the elegance, attractiveness and pliability of the shoe assembly.

Other objects and advantages are stated in the annexed description and drawing which illustrates a preferred embodiment thereof.

In the drawings:

Fig. 1 is a side-elevational view, in perspective, of the shoe in accordance with my invention;

Fig. 2 is a bottom plan view, with the outer sole partly broken away, thus exposing part of the platform sole;

Fig. 3 is a sectional detail view of the shoe, taken substantially on line 3—3 of Fig. 1; and

Fig. 4 is an enlarged sectional view, in perspective, of a portion of the lower part of the shoe.

Referring to the drawings, S indicates a shoe comprising an upper 1, a welt 2, an outer sole 4, and a wedge heel 5. Said upper 1 may be made of fabric, leather or other suitable material.

As clearly illustrated in Fig. 3, which shows in detail all the parts of the assembly and their respective connections, the base of the shoe comprises the sock lining 9, the platform sole 6, the narrow insert or cushion member 8, and the outer sole 4. The platform sole 6 is cemented to the bottom of sock lining 9, and outer sole 4 is cemented to platform sole 6 and insert member 8. The purpose of providing insert or cushion member 8 is to mollify the tread.

Platform sole 6 may be made of flexible materials, such as cardboard, cork, sponge rubber, felt,

2

etc. Insert member 8 can be made of felt, cork, etc. The sole 4 can be made of leather or any other suitable material.

Sock lining 9 is folded at its side marginal edges to form the folds 10, the tucked in portions of which abuts lining 11 of upper 1. The sock lining 9 and the upper lining 11 may be made of identical or different material, such as of thin and flexible fabric or leather.

10 As clearly shown in Figs. 3 and 4, the sides of platform sole 6 are snugly encased by a welting 2, said welting being formed of an elongated single strip of leather, fabric or other suitable material. The top marginal edge of said welting 2 is tucked or bent inwardly and downwardly to form the depending edge strip portion 12, said portion 12 abutting the bottom edge of upper 1. The sock lining 9, upper 1 and welting 2 are connected to each other by the through-and-through 20 stitches 13 which pass through fold 10, lining 11, upper 1 and edge strip 12.

Welting 2 is folded inwardly at its lower end to form the depending crease 14, the crease being prevented from unfolding by the seam 14'. 25 Crease 14 and seam 14' produce the bead or rib 3, said bead or rib terminating in the horizontal edge 15. This edge strip 15 is cemented and stitched to the outer sole 4 by means of the through-and-through stitches 16.

30 As shown in Fig. 1, welting 2 and its integral bead or rib 3 extends completely around the entire shoe S. It extends around the forepart of the shoe up to the arch thereof and then follows the beveled path of the upper portion of wedge heel 5 on both sides of the shoe. The marginal edge strip 15 extends around the forward end of the shoe up to point 17 substantially up to the arch of the shoe. The stitching 16 which connects said strip 15 with outer sole 4, terminates 40 at point 17 on both sides of the shoe. Starting at said point 17, the lower edge of bead or rib 3 is then tucked inwardly and cemented to the upper edge of wedge heel 5 and continues around the other side of the shoe up to a point opposite point 17.

Fig. 4, which illustrates an enlarged sectional view, in perspective, of a portion of the base of the improved shoe, strikingly emphasizes the smartness as well as the utility of the improved 50 construction. The shoe is rendered waterproof at the juncture of marginal edge strip 15 of welting 2 with the outer sole 4. This is the point which is primarily exposed to the ingress of water and mud. With the improved construction, a water-proof seal is provided at this junction point.

It will be understood that I do not wish to be limited to the precise structure as described and disclosed in the illustrated embodiment, but that I desire to avail myself of all such variations as might come within the scope of the appended claims.

What I claim is:

1. A platform shoe assembly comprising an upper unit, a wedge heel, a sock lining, a platform sole, an outer sole, and a welting strip, the upper margin of said welt being folded to a flap engaging the lower outer portion of the upper and secured thereto by stitches extending therethrough to the inner part of the upper unit and through the sock lining, the lower portion of said welt being creased inwardly and seamed to form a bead over its entire length, said bead terminating in an outwardly extending horizontal marginal edge, said marginal edge being secured to the outer sole. 15

2. A platform shoe assembly comprising an upper unit, a wedge heel, a sock lining, a platform sole, an outer sole, and an insert disposed between said outer and said platform soles, said platform sole being snugly encased by a welting strip, the 20 25

upper margin of said welt being folded to form a flap engaging the lower outer portion of the upper and secured thereto by stitches extending therethrough to the inner part of the upper unit and through the sock lining, the lower portion of said welt being creased inwardly and seamed to form a rib over its entire length, said rib terminating in a lateral flat marginal edge, said marginal edge being securely attached to the outer sole portion up to the arch of the shoe, the inwardly folded continuation of said rib extending over the top portion of the heel and being tucked under the platform sole and cemented thereto over the entire extension of said wedge heel portion. 15
